Patented Apr. 22, 1924.

1,491,467

UNITED STATES PATENT OFFICE.

ISRAEL K. DIXON, OF JOHNSTOWN, PENNSYLVANIA.

TONGUE SWITCH.

Application filed January 9, 1924. Serial No. 685,288.

To all whom it may concern:

Be it known that I, ISRAEL K. DIXON, a citizen of the United States, and resident of Johnstown, in the county of Cambria and 5 State of Pennsylvania, have invented certain new and useful Improvements in Tongue Switches, of which the following is a specification.

This invention relates to switches and 10 more particularly to tongue switches, and has for its object the provision of a novel form of tongue retaining mechanism for holding the tongue down to its seat, and allowing free movement of the tongue about 15 its center.

Another object is to provide a novel tongue retaining mechanism which is free 20 from bolts or nuts, and yet is adjustable vertically to compensate for wear.

25 A further object is to provide a novel retaining mechanism having sufficient resiliency or spring to automatically follow up the ordinary wear of the switch tongue and seat, thus preventing the tongue becoming loose and pounding the seat.

A still further object is to provide a switch having the novel design, construction, and combination of parts, hereinafter described in detail and illustrated in the 30 accompanying drawings.

In the drawings, Figure 1 is a plan of the heel or pivot end of a tongue switch structure having my invention applied thereto.

35 Figure 2 is a sectional elevation through the switch heel on the line II—II of Figure 1.

Referring more particularly to the drawings, the numeral 2 designates the switch 40 body, which is provided with a longitudinal groove or recess 3 forming a tongue bed, and said recess terminates at its rear end in a circular depression 4 forming a heel bearing 4.

45 A tongue 5 is mounted in the recess 3 and terminates at its rear end in an enlarged circular hollow heel 6, which is seated in the heel bearing depression 4.

50 At the side of the switch body 2 and in front of the tongue center, is a box 7, the purpose of which will be described.

The side walls of the heel bearing depression and the side walls of the hollow heel 6 are provided with aligned openings 8—9 55 and 10—11, respectively, at diametrically opposite points and a resilient or spring re-

taining lever 12 is projected through the openings 8—9 and 10—11. The lever 12 is provided intermediate its ends with a rounded fulcrum bearing 13 which is engaged against a circular seat 14 formed in the bottom wall of the heel 6 by beveling or rounding off the upper edge of an opening 15 formed in the center of the bottom wall of the heel which is on or near the gage line of the tongue. The one end of the lever 12 is adapted to bear against the upper face of the opening 9 in the heel bearing, while the opposite end of the lever tapers downwardly toward its end, and is 60 provided with a plurality of serrations or teeth 17 adapted to mesh with similar teeth 18 on the bottom face of a wedge shaped adjusting block 19, which is adapted to be mounted on the upper face of the lever. 65

By applying pressure to the upper face of the block 19 the lever 12 will be rocked about its fulcrum bearing 13 and its opposite end will be forced against the upper face of the opening 9, and if the pressure 70 is continued the fulcrum bearing will be forced against the seat 14 so as to hold the switch tongue heel 6 against its bearing. 75

In order to apply pressure to the block 19 I have provided a latch or lever operated cam 21 which also locks the lever under tension against the heel 6. 80

The end of the lever 12 carrying the block 19 projects into the box 7 and the latch 21 is mounted in this box and comprises a cam 85 shaped head 22, a curved lever portion 23 and horizontal spindles 24 and 25.

The side walls of the box 7 are provided with bearing slots 26 and 27, respectively, adapted to receive the spindles 24 and 25 90 of the latch. The spindle 24 and slot 26 are of greater length than the spindle 25 and slot 27, so that the latch may be moved bodily toward the switch body a sufficient distance to move the spindle 25 out of the slot 27, thereby facilitating the removal of 95 the latch. 100

The head 22 is so shaped that when the lever portion 23 is in its lowermost position the head will have moved slightly past its 105 center or highest point, so that it is self locking and will lock the fulcrumed lever 12 under tension against the heel 6.

In operation the block 19 will be adjusted to a position where the head 22 will bear 110 sufficiently on the block to properly tension the lever 12, and the latch will then be

forced down to locked position, thus forcing the lever 12 against the heel 6 and causing said heel to bear tightly against its bearing.

5 Due to the tension applied to the spring or resilient lever the tongue heel 6 will remain firm on its seat, since ordinary wear will be automatically taken up by the spring of the lever. However, when the wear becomes too great to be compensated for by the tension or spring of the lever, the block 19 may be adjusted to a higher position, so as to increase the tension on the lever 12.

10 The present invention, besides being superior to the forms of heel retaining devices heretofore used, in that it automatically compensates for wear and prevents pounding, is also superior in that it employs no bolts, nuts or other threaded members which 20 might work loose.

15 I claim:—

20 1. A tongue switch comprising a switch body, a tongue mounted in a suitable groove in said body, a hollow circular heel formed on the rear end of said tongue, a retaining lever fulcrumed against the bottom wall of said hollow heel and projecting through the side walls thereof, and adapted to have one end engaged against a portion of said 25 switch body, and a latch member adapted to bear against the opposite end of said lever and force the fulcrumed point thereof down against said heel.

30 2. A tongue switch comprising a switch body, a tongue mounted in a suitable groove in said body, a hollow circular heel formed on the rear end of said tongue, a retaining lever fulcrumed against the bottom wall of said hollow heel and projecting through 35 the side walls thereof and adapted to have one end engaged against a portion of said switch body, a latch member adapted to bear against the opposite end of said lever to force the fulcrum point of said lever 40 against said heel and thereby force said heel into its seat, and means for locking said latch in position.

45 3. A tongue switch comprising a switch body, a tongue mounted in a suitable groove 50 in said body, a hollow circular heel formed on the rear end of said tongue, a retaining lever fulcrumed against the bottom wall of said hollow heel and projecting through the side walls thereof, and adapted to have 55 one end engaged against a portion of said switch body, a latch member having a cam shaped head adapted to be rocked against the opposite end of said lever to tension the fulcrum point of said lever against said

60 heel and thereby force said heel into its seat, said cam shaped head being adapted to be moved past its highest point to lock said lever in its tensioned position.

65 4. A tongue switch comprising a switch body, a tongue mounted in a suitable groove in said body, a hollow circular heel formed on the rear end of said tongue, a retaining lever fulcrumed against the bottom wall of said hollow heel and projecting through the side walls thereof, and adapted to have 70 one end engaged against a portion of said switch body, a latch member having a cam shaped head adapted to be rocked against the opposite end of said lever to tension the fulcrum point of said lever against said 75 heel and thereby force said heel into its seat, said cam shaped head being adapted to be moved past its highest point to lock said lever in its tensioned position, and an adjustable wedge shaped member mounted on 80 the end of said lever adapted to be engaged by said latch, said member being adjustable longitudinally of said lever to vary the tensioning effect of said latch.

85 5. A tongue switch comprising a switch body, a tongue mounted in a suitable groove in said body, a circular heel portion formed on the rear end of said tongue and mounted for rotation in a suitable circular recess in said switch body, a resilient or spring lever 90 fulcrumed on said heel at a point near the gage line of the tongue, means for tensioning said lever downwardly against said switch body, and means for adjusting the tension of said lever.

95 6. A tongue switch comprising a switch body having a longitudinal recess therein forming a tongue bed, said recess terminating at its rear end in a circular depression forming a heel bearing, a tongue mounted 100 in said longitudinal recess and provided at its rear end with a hollow circular heel portion adapted to be seated in said heel bearing recess, a resilient or spring retaining lever extending through suitable openings in the 105 side walls of said hollow heel and projecting outwardly from each side thereof, said lever being fulcrumed against the bottom wall of said heel at a point near the gage line of said tongue and having one end engaged against a portion of said switch body, 110 means for applying pressure against the opposite end of said lever to tension said lever downwardly against said heel bearing, and means for adjusting the tension of said lever. 115

In testimony whereof, I have hereunto set my hand,

ISRAEL K. DIXON.
